U.S. Cl. D26—14 C

Fig. 1

Fig. 2

Fig. 3

FIG. 1 is a front elevational view of a front panel for chart recorder, showing our new design.

FIG. 2 is a top plan view thereof.

FIG. 3 is a right side view thereof.

The left side is a mirror image of the right side.

The bottom and rear sides of the device are substantially plain and unornamented.

The broken line disclosure of the display numerals in FIG. 1 is for illustrative purposes only and forms no part of the claimed design.

We claim:

The ornamental design for a front panel for chart recorder, as shown and described.
